UNITED STATES PATENT OFFICE.

CHARLES A. WAY, OF NORTH CHARLESTOWN, NEW HAMPSHIRE.

SNOW-SHOVEL.

SPECIFICATION forming part of Letters Patent No. 252,822, dated January 24, 1882.

Application filed October 31, 1881. (Model.)

To all whom it may concern:

Be it known that I, CHARLES A. WAY, a citizen of the United States, residing at North Charlestown, in the county of Sullivan and State 5 of New Hampshire, have invented certain Improvements in Snow-Shovels, of which the following is a full, clear, and exact description, reference being had to the accompanying drawings, making part of this specification, in 10 which—

Figure 1 is a perspective view of a snow-shovel constructed in accordance with my invention. Fig. 2 is a longitudinal vertical section through the same. Fig. 3 is a transverse 15 vertical section on the line $x-x$ of Fig. 2. Fig. 4 is a plan of the upper portion of the under side of the blade; Fig. 5, sectional detail enlarged.

My invention relates to certain improvements in snow-shovels, and has for its object 20 to secure greater strength and durability in the fastening by means of which the handle is secured to the blade.

In snow-shovels of the ordinary construction 25 a bolt passing through the handle about three inches from its lower end is employed to secure it to the blade, which latter is provided with a small metallic socket to receive the extreme end of the handle and prevent it from having 30 any lateral motion. This bolt, however, is objectionable, as its diameter is necessarily large to insure the requisite degree of strength, and consequently its passage through the handle materially weakens the latter at the point where 35 it is subjected to the greatest strain.

To remove this difficulty is the object of my invention, which consists in securing the handle of the shovel to the blade by means of a curved metallic clasp or clip which is adapted 40 to fit over the lower end of the handle, and is provided with flanges on its sides, through which pass bolts which extend through the blade and are riveted on a plate on the under side thereof, a single bolt or rivet passing 45 through the end of the handle close to the tip and through the blade for the purpose of preventing the handle from being withdrawn or pulled out of the clasp.

In the said drawings, A represents the 50 wooden blade of the shovel, to the upper end of which is secured the ordinary cleat, b.

B is the handle, the under side of the lower

end of which is chamfered off, as usual, to enable it to fit snugly upon the surface of the cleat b.

C is a strong metallic clasp or clip, preferably of malleable iron, which is adapted to fit over the lower end of the handle, as seen in Fig. 1, and is provided on each side with a flange or ear, a, through which passes a bolt, d, which extends through the cleat b and blade A, and also through a metallic plate, D, placed against the under side of the blade, the bolts d being riveted on this plate D, as seen in Figs. 3 and 4. The clasp C, when thus secured in 65 place, serves to firmly hold the handle which it embraces; and to prevent the handle from being pulled out of the clasp C, and also from having any lateral motion, a bolt, f, is employed, which passes through an aperture at 70 the lower end of the clasp, and also through the thin part of the chamfered end of the handle close to the tip, the cleat b, blade A, and plate D, the lower end of the bolt being riveted on the latter, as seen in Fig. 2.

It will be seen from the foregoing that the clasp C, secured as above described, forms a strong, simple, and durable fastening for the handle, which is thus left of full strength at the point where it is subjected to the greatest 80 strain, the bolt f in no wise impairing its strength, as it merely passes through the thin portion close to the tip, where there is little or no strain.

On the inner surface of the clasp C are two 85 sharp projections, g, which enter a short distance into the handle and serve to hold it with additional steadiness; but these projections may be dispensed with, if desired.

E is the metallic tip or shoe, which is applied 90 to the lower end of the blade A. This shoe, which is preferably composed of malleable iron, is provided with a centrally-projecting tongue or tenon, h, which fits into a corresponding groove, i, formed at the lower end of 95 the blade A, and is secured in place by rivets k, which pass through the wood at a point sufficiently distant from its edge, and where it is of such thickness as to afford the necessary strength. The upper edges of the tip or shoe 100 E are beveled or inclined inward on each side of the tongue h from l to m, as seen in Figs. 1, 2, and 5, and fit over the correspondingly-beveled edges n n of the blade A, against which

they abut; and by this construction the end of the blade is securely protected from injury, and the liability of the wood being split or broken away, as often occurs in ordinary snow shovels, is thus entirely avoided, while the end of the blade A can be left of much greater thickness than has heretofore been possible where tips of the ordinary construction are employed, and consequently there is no liability of the rivets being pulled through the wood and the tip becoming loose or detached from the blade, as heretofore.

What I claim as my invention, and desire to secure by Letters Patent, is—

15 In a snow-shovel, the combination, with the blade A and handle B, of the metallic clasp C,

provided on its sides with flanges or ears a, secured in place by bolts d d, passing through said ears and the blade, and riveted upon the plate D, and the bolt f, passing through the 20 end of the clasp, the thin portion of the chamfered end of the handle, and the blade A, and riveted on the triangular plate D, all constructed and arranged substantially in the manner and for the purpose set forth. 25

Witness my hand this 22d day of October, A. D. 1881.

CHARLES A. WAY.

In presence of—

W. A. HUNT,
R. J. HUNT.
